UNITED STATES PATENT OFFICE.

ISAAC R. DAVIES, OF LAKEWOOD, OHIO.

DESIGN FOR A VEHICLE-TIRE.

54,068.

Specification for Design.

Patented Nov. 4, 1919.

Application filed June 20, 1919. Serial No. 305,670. Term of patent 7 years.

To all whom it may concern:

Be it known that I, ISAAC R. DAVIES, a citizen of the United States, residing at Lakewood, county of Cuyahoga, and State of Ohio, have invented a new, original, and ornamental Design for Vehicle-Tires, of which the following is a specification, reference being had to the accompanying drawing, forming part thereof.

The figure is a perspective view of a portion of a rubber tire, showing my new design.

I claim:

The ornamental design for a vehicle tire, as shown.

ISAAC R. DAVIES.
